UNITED STATES PATENT OFFICE.

HARRY C. ZIMMERMAN, OF WASHINGTON, DISTRICT OF COLUMBIA.

TRAVERSING ROLLER.

Application filed September 20, 1923. Serial No. 663,905.

(FILED UNDER THE ACT OF MARCH 3, 1883, 22 STAT. L., 625.)

To all whom it may concern:

Be it known that I, HARRY C. ZIMMERMAN, a citizen of the United States, and a resident of Washington, D. C., have invented an Improvement in Traversing Rollers, of which the following is a specification.

The invention described herein may be used by the Government, or any of its officers or employees in prosecution of work for the Government, or by any other person in the United States, without payment to me of any royalty thereon, in accordance with the act of March 3, 1883.

The subject of this invention is a gun carriage and the invention relates more specifically to the traversing rollers for the carriage axle.

The primary object of my invention is the provision of means for use with a gun carriage axle which will carry the moving weight when traversing and which by a slight deflection under the force of firing permits a greater bearing upon the axle than is customary in traverse so as to provide additional means for taking up the shock of recoil and preventing damage to the traversing and elevating mechanism.

A further object is the provision of such means which will permit ready traverse of the gun carriage on a curved axle.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of my invention is illustrated in the accompanying drawing in which:

Fig. 1 is a section through the axle housing, and

Fig. 2 is a section taken at right angles to that shown in Fig. 1.

Fig. 3 is a plan view of the axle and axle housing, with the trail shown in dotted lines; and Fig 4 is a rear elevation of the axle and housing.

Referring to the drawing by numerals and reference:

I have shown the usual gun carriage axle 10 which may be an I-beam or round or of any other suitable shape. The axle 10 slides within a liner 11 secured to the axle housing 12 and is connected to the trail 9 of the gun carriage. Journaled in the axle housing is a pin 13 which in the preferred embodiment of my invention serves as a supporting means for a plurality of rollers 14. The rollers 14 are mounted so as to pass through an opening 15 formed in the liner 11 and bear directly upon the top surface of the axle 10 and in traverse these rollers carry the moving weight. These rollers 14 are mounted upon the pin 13 so as to move relative to each other, their relative movement permitting ready traverse of the housing 12 upon the axle where a curved axle such as shown in Fig. 3 and more specifically described in my co-pending application Ser. No. 663,908 filed September 20, 1923, is employed.

A removable cover 16 may be provided for the axle housing to keep out dust and dirt. The rollers 14 in normal position support the axle housing in such manner that the liner 11 is spaced from the axle itself and so that sufficient clearance is provided between the liner and the axle to permit ready traverse of the housing upon the axle. When the gun is fired, however, the pin 13 which is constructed of material sufficiently elastic to yield under the weight of the upper carriage with the force of firing is deflected in such a manner as to bring the liner into contact with the axle so as to provide a greater bearing surface for the housing upon the axle and in this manner to provide means whereby practically all the shocks of recoil may be transmitted directly to the gun carriage thus preventing possible damage to the elevating or traversing mechanism.

When my invention is used with a curved axle the movement of the rollers relative to each other is such that the housing may be readily traversed upon the axle.

The construction of my device is such

that it may be readily dismounted for cleaning, the pin 13 being removable from the housing in which it is normally retained by a cotter pin or a similar device and the 5 cover 16 being removable to permit ready access to the axle.

While I have preferred to use rollers in my device, it is obvious that any other suitable type of anti-friction means may be employed in their stead.

While I have described my invention as applied to a gun carriage it is obvious that it is by no means restricted to such a use and that it might be employed with any 15 other vehicle where it is desired to transmit any abnormal load entirely and directly to the axles.

I claim:

1. In combination, an axle bent intermediate its length, a housing for said axle, a liner in said housing, said liner provided with an opening, a plurality of rollers, adapted to pass through said opening and normally supporting said housing on said axle and 25 having the same axis of rotation and movable relative to one another in various rates of speed when said housing is traversed on said axle, mounted in said housing, means connecting said rollers to said housing, said

connecting means being adapted to be deflected when an abnormal force is applied to said housing to bring said liner into contact with said axle. 30

2. In combination, an axle bent intermediate its length, a housing for said axle, a liner in said housing, a plurality of rollers, normally supporting said housing on said axle and holding said liner out of contact with said axle and having the same axis of rotation and movable relative to one another 40 at various rates of speed when said housing is traversed on said axle, mounted in said housing, means connecting said rollers to said housing adapted to be deflected when an abnormal force is applied to said housing 45 to bring said liner into contact with said axle.

3. In combination, an axle bent intermediate its length, a housing for said axle, a plurality of rollers, adapted to support said 50 housing on said axle and adapted to have the same axis of rotation and to move relative to one another at various rates of speed when said housing is traversed on said axle mounted in said housing, and means connecting said rollers with said housing. 55

HARRY C. ZIMMERMAN.
